UNITED STATES PATENT OFFICE

2,414,956

ELECTROMAGNETIC SWITCH

William D. Kyle, Jr., Milwaukee, and Carl Schindler, Wauwatosa, Wis., assignors to Kyle Corporation, a corporation of Wisconsin

Original application June 6, 1941, Serial No. 396,850. Divided and this application July 22, 1943, Serial No. 495,682

10 Claims. (Cl. 200—111)

1

This invention relates to automatic reclosing circuit breakers and is a division of our application for Automatic reclosing circuit breakers Serial No. 396,850 filed June 6, 1941.

Objects of this invention are to provide an automatic reclosing circuit breaker which when it closes always comes back to a definite predetermined position irrespective of the number of operations or the wear of the parts, which has a wiping action of the contacts thereby maintaining good electrical contact without a gradual increase in resistance due to oxidation from arcing, in which independent readily renewable arcing contacts are provided which receive the final arc and thus avoid any injury to the main contacts, the construction being such that the circuit breaker will always operate at its predetermined overload value irrespective of the length of time it may have been in operation or the number of times that it has operated.

Embodiments of the invention are shown in the accompanying drawings, in which:

Figure 1 is a side elevation, partly broken away and partly in section, of the automatic reclosing circuit breaker.

Figure 2 is a fragmentary sectional view on the line 2—2 of Figure 1.

Figure 3 is a sectional view on the line 3—3 of Figure 2.

Figure 4 is a view corresponding to Figure 2 showing a further form of the invention.

Figure 5 is a view showing a still further form of the invention.

The circuit breaker is oil immersed and is mounted within the oil containing metal can 1 which is provided with a removable top 2 removably held to the can in any suitable manner. A convenient way of attaching the top to the can is by means of a plurality of bolts 3 which are pivotally mounted between spaced ears 4 carried by the can and which are provided with wing nuts 5. The wing nuts are adapted to bear against L-shaped clamping plates 6 whose downwardly extending portions are adapted to rest upon the upper faces of the ears 4, a suitable lug 7 being provided on each of the ears to prevent the clamping plates 6 from sliding off the upper surface of the ears 4. A suitable sealing gasket, not shown, is positioned between the can and the cover.

Any suitable attaching means as indicated at 8 and 9 are provided on the can so that the can may be attached to a pole or other suitable support.

The cap or cover 2 is provided with line and

2

load terminals which are carried by insulating bushings one of which is shown and indicated by the reference character 10.

The automatic reclosing circuit breaker is suspended in its entirety from the metal cover 2. The circuit breaker is provided with the electromagnetic coil or solenoid 11 which surrounds an insulating tube or sleeve 12.

A non-magnetic operating rod 13 for the circuit breaker extends upwardly centrally of the insulating tube 12 and on this rod a plunger 14 of magnetic material is freely slidable.

The operating rod 13 of the circuit breaker rigidly carries a spider like stop 15 which loosely fits within the sleeve 12 and which serves as an abutment against which the upper end of the magnetic plunger 14 strikes when the coil 11 is energized by an overload current. When this occurs, the plunger 14 is suddenly drawn upwardly into the coil and strikes the abutment 15, carrying the rod 13 upwardly.

The lower end of the rod 13 is rigidly secured to an insulating cross-head 16, see Figure 2. The cross-head 16 carries a pair of contact rods 17 to which are rigidly attached a pair of contact sleeves 18, see Figures 2 and 3. The contact sleeves 18 normally engage the stationary contact pins 19. These stationary contacts or contact pins 19 are connected to the line and load terminals of the circuit breaker.

It is to be noted particularly with reference to Figures 2 and 3 that the stationary contact pins 19 constitute stops against which the lower ends of the contact rods 17 abut when the circuit breaker is closed.

It is preferable to make the contact pins or stationary contacts 19 split as shown in Figure 3 and to have the movable contacts or sleeves 18 engage the pins 19 with a wiping motion to insure a clean contact at all times. The arcing upon separation of the movable and stationary contacts does not occur between the sleeves 18 and the pins 19 but separate arcing contacts are provided in the form of conducting rollers 20 which may be of metal and which are carried by leaf springs 21 clamped in place as shown in Figure 3. These arcing contacts 20 are the last members that engage the movable contacts 18. All the arcing occurs between the arcing contacts 20 and the outer surfaces of the sleeves 18, thus maintaining the inner surfaces of the sleeves and the outer surfaces of the pins in good condition free from pitting although the circuit breaker may have operated a great number of times.

The arcing contacts are readily renewable and

It is also easy to renew the sleeves 18, if this becomes necessary, by driving out the locking pin or other suitable securing means 22, see Figure 3, and replacing the old sleeves with new sleeves. This very rarely happens, however, for the arcing occurs, as stated, between the outer surfaces of the sleeves 18 and the arcing contacts 20.

It is to be noted particularly that the upper ends of the stationary contacts or pins 19 form a definite stop for arresting the downward motion of the movable portions of the circuit breaker and consequently the circuit breaker, together with the magnetic core or plunger 14, see Figure 1, will always come to rest at exactly the same point so that the circuit breaker will always respond to the same current.

If, on the other hand, the active contact had been a butt contact and the arcing had occurred between butt contacts there would be a gradual wearing away of this contact through continued use of the circuit breaker and consequently the circuit breaker would operate only at an increased current as the time of service increased. However, in the invention herein described, the circuit breaker will always respond at exactly the same predetermined value of overload current.

The contact rods 17 are connected by flexible leaders 23 with opposite ends of the coil 11 so that the coil 11 is in series between the line and load terminals and directly across the movable contacts 18.

It is preferable to encase the lower portion of the circuit breaker, that is to say, the stationary and movable contacts, within an insulating cylindrical sleeve 24. The upper end of the sleeve 24 is closed, except for passageways which form no portion of the present invention, by means of the collar or member 25 and the lower end of the sleeve 24 is closed by means of the base member 26. The base member is provided with an oil inlet opening 27, see Figure 1, which is normally closed by a downwardly seating flap 28.

As will be seen from Figure 2, the insulating base member 26 is suspended by means of the insulating rods 29. These rods extend upwardly to the portion 25 and are internally threaded at their upper and lower ends to receive the bolts to thereby lock the rods in place and to the base 26. The insulating sleeve or shell 24 is therefore clamped between the insulating head or collar 25 and the insulating base 26.

It is preferable to provide insulating partitions extending upwardly between the spaced contacts. These partitions may take the form of two members 30 of insulating material which have integrally formed, outwardly bent foot portions 31, see Figure 2. The foot portions are clamped in place by the stationary contacts. The member 30 may be in contact with each other, as shown in Figure 2, or may be spaced apart, as shown in Figure 4, or may be spaced apart at their lower ends and may approach each other or be in contact at their upper ends, as shown in Figure 5.

By having the base or foot portions 31 of the members or baffles 30 integral with the vertical portions thereof, it is apparent that any conducting sediment that may settle down between the stationary contacts will not form a bridge path from one contact to the other. Further, in view of the fact that the members 30 and 31 are integral, it is apparent that no conducting sediment can form and lead up to a short gap across which the arc would strike.

In Figure 4 a different form of insulating baf-

file has been illustrated. These baffles have the same shape as those previously described and consist of the vertical portions 32 and the horizontal foot portions 33, but these baffles are spaced apart to allow an oil space between the baffles.

The baffles may also take another form as shown in Figure 5, in which the upright portions of the insulating baffles are indicated at 34 and the foot portions or horizontal portions at 35. The upstanding portions 34 may engage each other at their upper ends but are spaced at their lower ends to provide an oil space.

The circuit breaker is automatic in its operation and is adapted to look out after a certain number of operations and has oil cushioning means and oil pumping means and automatic and manual trip means, as well as manual reset means, but inasmuch as these features form no portion of this invention, a description and disclosure thereof has been omitted. These features are, however, as set forth in our companion case hereinbefore identified of which this application is a division.

Suffice is to say that when an overload occurs, the plunger 14 is drawn upwardly and strikes the spider like stop 15 rigid with the rod 18 and raises the cross-head 16, which raises the rigidly attached contact rods 17 and consequently moves the movable contacts or sleeves 18 from the stationary contacts or pins 19, the last contact being established through the outer surface of the sleeves 18 and the arcing contacts 20, the arcing, therefore, being confined to the outer surface of the sleeves 18.

It is apparent that for any given winding or solenoid 11 the minimum overload current at which the plunger 14 will be drawn upwardly into the solenoid will be determined by the position of the upper end of the plunger 14 within the solenoid. Consequently it is desirable to always bring the plunger 14 to rest at exactly the same point when the circuit breaker is closed. This is accomplished by having the contact rods 17 abut the upper ends of the stationary contacts or pins 19 but having the current carrying portions between the sliding sleeves 18 and the pins 19 so that the circuit is never broken at the abutting surfaces of the contact rods 18 and the pins 19 and consequently no pitting or wear from such cause can result at this point. In view of the fact that these contact surfaces are merely abutting contact surfaces, there is scarcely any mechanical wear whatsoever, and therefore even after the circuit breaker has been in use for a long period and has operated a great many times, nevertheless it will always open for the predetermined minimum overload current.

It is also apparent that in the event the outer surfaces of the sleeve 18 or the arcing contacts 20 may have become seriously pitted, they can be most easily renewed.

In the form of the invention shown in Figure 4 a metal cross-head 16' has been provided and is rigidly attached to the metal rods 17. With this type of construction the two stationary contacts are connected respectively to a line terminal and to one side of the solenoid 11, the other side of the solenoid 11 being connected to the load terminal.

Although this invention has been described in considerable detail, it is to be understood that such description is intended as illustrative rather than limiting, as the invention may be variously embodied and is to be interpreted as claimed.

We claim:

1. A circuit breaker comprising a stationary contact and a movable contact, and electromagnetic means for moving said movable contact away from said stationary contact including a coil and a cooperating armature, said stationary contact and said movable contact having abutting portions constituting stop means to maintain a predetermined definite relation between said armature and coil when said contacts are closed irrespective of the wear on the contacts due to arcing, said contacts having slidably engaging portions constituting wiping contacts for carrying the current.

2. A circuit breaker comprising a stationary contact and a movable contact, and electromagnetic means for moving said movable contact away from said stationary contact including a coil and a cooperating armature, said stationary contact and said movable contact having abutting portions constituting stop means to maintain a predetermined definite relation between said armature and coil when said contacts are closed irrespective of the wear on the contacts due to arcing, said contacts having slidably engaging portions constituting wiping contacts for carrying the current and one of said contacts having arcing contact means for engaging the outer side of the other contact to locate the final arc at a point spaced from both the stop means and the slidably engaging portions.

3. A circuit breaker comprising a stationary contact and a movable contact, electromagnetic means for moving said movable contact away from said stationary contact including a coil and a cooperating armature, said stationary contact and said movable contact having abutting portions constituting stop means to maintain a predetermined definite relation between said armature and coil when said contacts are closed irrespective of the wear on the contacts due to arcing, one of said contacts being in the form of a pin and the other of said contacts being in the form of a sleeve having sliding engagement with the pin to provide the current carrying portions of said contacts.

4. A circuit breaker comprising a stationary contact and a movable contact, electromagnetic means for moving said movable contact away from said stationary contact including a coil and a cooperating armature, said stationary contact and said movable contact having abutting portions constituting stop means to maintain a predetermined definite relation between said armature and coil when said contacts are closed irrespective of the wear on the contacts due to arcing, one of said contacts being in the form of a pin and the other of said contacts being in the form of a sleeve having sliding engagement with the pin to provide the current carrying portions of said contacts, the contact in the form of a pin having an arcing contact adapted to maintain engagement with the outer surface of said sleeve for an instant after said sleeve and pin have separated.

5. A circuit breaker comprising a stationary contact and a movable contact, electromagnetic means for moving said movable contact away from said stationary contact including a coil and a cooperating armature, said stationary contact and said movable contact having abutting portions constituting stop means to maintain a predetermined definite relation between said armature and coil when said contacts are closed irrespective of the wear on the contacts due to arcing,

one of said contacts being in the form of a pin and the other of said contacts being in the form of a sleeve having sliding engagement with the pin to provide the current carrying portions of said contacts, one of said contacts being split.

6. A circuit breaker comprising a stationary contact and a movable contact, electromagnetic means for moving said movable contact away from said stationary contact including a coil and a cooperating armature, said stationary contact and said movable contact having abutting portions constituting stop means to maintain a predetermined definite relation between said armature and coil when said contacts are closed irrespective of the wear on the contacts due to arcing, one of said contacts being in the form of a pin and the other of said contacts being in the form of a sleeve having sliding engagement with the pin to provide the current carrying portions of said contacts, a pair of leaf springs on opposite sides of said pin, and arcing contacts carried by said leaf springs and adapted to grip said sleeve between them and maintaining contact with the outer surface of said sleeve for an instant after said sleeve and pin have been separated.

7. A circuit breaker comprising a stationary contact and a movable contact, electromagnetic means for moving said movable contact away from said stationary contact including a coil and a cooperating armature, said stationary contact and said movable contact having abutting portions constituting stop means to maintain a predetermined definite relation between said armature and coil when said contacts are closed irrespective of the wear on the contacts due to arcing, one of said contacts being in the form of a rod with a sleeve surrounding and extending from the outer end thereof, and the other contact being in the form of a pin slidably receiving said sleeve when said contacts are closed and constituting the current carrying portion of said contacts, the rod and pin having ends adapted to abut to determine the initial position of said armature with reference to said coil.

8. In a switch construction, switch means including a stationary contact and a movable contact, and means for moving said movable contact with reference to said stationary contact, said stationary contact and said movable contact having abutting portions constituting stop means to maintain a predetermined definite relation between said movable contact and said stationary contact when said switch means is closed irrespective of wear on the contacts due to arcing, one of said contacts being in the form of a pin and the other of said contacts being in the form of a sleeve having sliding engagement with the pin to provide the current carrying portions of said contacts, the contact in the form of a pin having an arcing contact adapted to maintain engagement with the outer surface of said sleeve for an instant after said sleeve and pin have separated.

9. In a switch construction, switch means including a stationary contact and a movable contact, and means for moving said movable contact with reference to said stationary contact, said stationary contact and said movable contact having abutting portions constituting stop means to maintain a predetermined definite relation between said movable contact and said stationary contact when said switch means is closed irrespective of wear on the contacts due to arcing, one of said contacts being in the form of a rod with a sleeve surrounding and extending from

the outer end thereof and the other contact being in the form of a pin slidably receiving said sleeve when said contacts are closed and constituting the current carrying portion of said contacts, the rod and pin having ends adapted to abut to determine the position of said movable contact with reference to said stationary contact when said switch means is closed.

10. A switch construction comprising a stationary contact and a movable contact, and means for moving said movable contact with

reference to said stationary contact, one of said contacts being in the form of a pin and the other of said contacts being in the form of a sleeve having sliding engagement with the pin to provide the current carrying portion of said contacts, the contact in the form of a pin having an arcing contact adapted to maintain engagement with the outer surface of said sleeve for an instant after said sleeve and pin have separated.
